UNITED STATES PATENT OFFICE.

CHARLES F. TROMMER, OF NEW YORK, N. Y., ASSIGNOR TO A. WITTNauer CO., OF NEW YORK, N. Y.

BRACELET.

1,120,563.

Specification of Letters Patent.

Patented Dec. 8, 1914.

Application filed February 18, 1913, Serial No. 749,132. Renewed November 2, 1914. Serial No. 869,972.

To all whom it may concern:

Be it known that I, CHARLES F. TROMMER, a citizen of the United States, and a resident of the city of New York, borough of Queens, 5 in the county of Queens and State of New York, have invented a new and Improved Bracelet, of which the following is a full, clear, and exact description.

The invention relates to jewelry and its 10 object is to provide a new and improved bracelet formed of sections connected with each other by normally concealed means which allow the bracelet to enlarge in diameter when pushing it over the hand onto 15 the wrist, and to then contract automatically when reaching the wrist so that the bracelet is not liable to accidentally slip off the arm and become lost.

In order to accomplish the desired result 20 use is made of hollow sections and yielding connecting means connecting the sections with each other and normally concealed within the hollow sections.

A practical embodiment of the invention 25 is represented in the accompanying drawings forming a part of this specification, in which similar characters of reference indicate corresponding parts in all the views.

Figure 1 is a perspective view of the 30 bracelet constructed according to my improvements; Fig. 2 is a perspective view of the improved bracelet provided with a watch; Fig. 3 is an enlarged perspective view of a number of sections of the bracelet 35 let with two adjacent sections drawn apart; Fig. 4 is a sectional side elevation of a portion of the bracelet, parts being shown in elevation; Fig. 5 is a side elevation of the bracelet with some of the sections drawn 40 apart and in angular position one relative to the other, one of the links being shown in section; and Fig. 6 is a perspective view of a portion of the bracelet shown in Fig. 2.

The bracelet shown in Fig. 1 is formed of 45 a number of segmental sections A made hollow and each open at one end A' and closed at the other end A'', as plainly shown in Figs. 4 and 5. The closed end A'' of a section H is provided at its outer face with 50 an integral eye B adapted to fit into the open end A' of the next adjacent section A and the said eye B is engaged by one end C' of a segmental link C slidingly fitting the adjacent section A. The coil spring D is arranged in the opening of the link C and the

inner end of the spring D presses against the inner end C' of the link C while the outer forward end of the said spring D abuts against a pin E held on the top and bottom of the corresponding section A a 60 distance from the open end A' thereof. By the arrangement described the spring D exerts an inward pressure on the link C so as to normally hold the said link withdrawn within the section A and with it the eye B 65 of the adjacent section (see Fig. 4.) The end C' of the link C engaging the eye B is preferably round in cross section so that a universal joint is formed by the end C' and the eye B to permit of swinging a section 70 into any angular position relative to its mate whenever the sections are drawn apart, as will be readily understood by reference to Fig. 5. Thus when the sections are drawn apart they can readily assume any 75 angular position one relative to the other to permit of conveniently slipping the bracelet over the hand onto the wrist, it being understood that during the time the bracelet is slipped over the hand the sections A 80 are drawn apart and the diameter of the bracelet is increased, and as soon as the bracelet reaches the wrist portion the several springs D return the sections to normal position with the end of one section abutting 85 against the end of the adjacent section as shown in Fig. 1. It will be noticed that when the adjacent sections are in closed position the closed end A'' of one section closes the open end A' of the adjacent section so 90 that dust and other extraneous matter are not liable to pass into the hollow sections. The eye B of a section is so shaped that its top and bottom faces fit against the inner surfaces of the top and bottom of the open 95 end A' to prevent the sections from turning one on the other at the time the sections are closed.

From the foregoing it will be seen that the hollow sections of the bracelet are connected with each other by yielding means normally concealed within the hollow sections and arranged to permit of expanding the bracelet whenever it is desired to do so, that is, when slipping it over the hand on 100 placing the bracelet in position on the wrist or arm or when removing it therefrom.

The bracelet shown in Fig. 2 is formed of 105 a number of sections A the same as the sections above described in reference to Figs. 110

1, 3, 4 and 5, and in addition to the sections A use is made of a section F in the form of a watch or ornament provided at opposite sides with loops G engaging the eyes B of 5 adjacent sections A. It will be noticed that in this arrangement two adjacent sections have their open ends A' adjacent (see Fig. 6), and in order to make a yielding connection between the sections use is made of a 10 plate H provided on opposite sides with eyes B' engaged by the ends C' of the links C contained in the adjacent sections A.

It will be noticed by reference to Fig. 2 that when the sections are in normal condition, the plate A closes the adjacent open ends A' of the sections referred to and shown in Fig. 6.

Having thus described my invention, I claim as new and desire to secure by Letters Patent:

1. A bracelet, comprising hollow sections each open at one end and closed at the other end, the closed end having an eye projecting therefrom and adapted to pass into the 25 open end of the adjacent section, links each formed of spaced side members and end members, one end member being curved and round in cross section and engaging the eye of one section and extending into the adjacent section, a pin in each section adjacent its open end and extending between the side members of the link in said section, and a spring in each between the side members of the link and pressing with one end on the 30 end of the link and with its other end on the said pin.

2. A bracelet having hollow sections each open at one end and closed at the other end, the closed end having a centrally arranged eye adapted to pass into the open end of the 40 next adjacent section, the said eye normally engaging with two opposite sides the inner faces of corresponding sides of the adjacent section to hold the sections against turning one relative to the other, links each formed 45 of spaced side members and end members and having one end member loosely engaging the eye of one section and extending into the next adjacent section, and a spring within each section and pressing the link 50 therein.

3. A bracelet having hollow sections each open at one end and closed at the other end, the closed end having a centrally arranged eye adapted to pass into the open end of the 55 next adjacent section, links each formed of spaced side members and end members and engaging the eye of one section and extending into the next adjacent section, the end 60 of the link engaging the eye being round in cross section and forming with the eye a universal joint to allow the sections to swing in any direction when the sections are drawn apart, and a spring within each section and pressing the link therein. 65

In testimony whereof I have signed my name to this specification in the presence of two subscribing witnesses.

CHARLES F. TROMMER.
